R. V. Jones,

Shutter Worker.

No 9,405. Patented Nov 16, 1852.

UNITED STATES PATENT OFFICE.

ROBERT V. JONES, OF BIRMINGHAM, PENNSYLVANIA.

BLIND AND SHUTTER OPERATOR.

Specification of Letters Patent No. 9,405, dated November 16, 1852.

To all whom it may concern:

Be it known that I, ROBERT V. JONES, of the borough of Birmingham, in the county of Allegheny and State of Pennsylvania, have invented a new and useful Machine for Opening and Closing and Fastening Window-Shutters by Means of a Roller and Chain; and I do hereby declare that the following is a full, clear, and exact description of the construction and operation of the same, reference being had to the annexed drawings, making a part of this specification, in which—

Figure 1 is a view of the hinge when shut and Fig. 2 is a view of the same when opened.

To enable others skilled in the art to make and use my invention I will proceed more fully to describe its construction and operation.

It is intended to be applied to the ordinary windows and shutters of dwellings, &c. now commonly used. I use a cap, letter *a*, Fig. 1, made of cast iron, working on a cast iron box, letter *b* Fig. 1, the two together making what I term a box hinge, and is at-

tached to the shutters with ordinary wood screws by the flange, letter *c*, Fig. 1, letter *f* represents a wrought iron chain working around a roller in the box hinge also working upon another roller, letter *e* Fig. 1, the roller *e*, like the other being made of cast iron and working and supported by a cast iron frame attached with wood screws to the window frame, the whole when so arranged is operated upon and moved by the handle *d* Fig. 1. Fig. 2 is a view of the hinge when opened the same letters referring to like parts as in Fig. 1.

What I claim as my invention and desire to be secured by Letters Patent is—

The tubular shanked box hinge, with roller contained therein as arranged with respect to the roller within the building when the rollers are connected by a chain and the whole is constructed as herein described, constituting a convenient blind, or shutter operator.

R. V. JONES.
